(57) **CLAIM**

The ornamental design for an aeration nozzle, as shown and described.

DESCRIPTION

FIG. 1 is a reference front elevational view of an aeration nozzle, showing the aeration nozzle when being used;

FIG. 2 is a elevational view, showing my design in solid lines;

FIG. 3 is a back elevational view, showing my design in solid lines;

FIG. 4 is a right side view, showing my design in solid lines;

FIG. 5 is a left side view, showing my design in solid lines;

FIG. 6 is top plan view, showing my design in solid lines;

FIG. 7 is a bottom plan view, showing my design in solid lines

FIG. 8 is a perspective view of A-A line in the direction of the arrow, showing my design in solid lines;

FIG. 9 is a perspective view of B-B line in the direction of the arrow, showing my design in solid lines; and,

FIG. 10 is a cross sectional view along C-C line in the direction of the arrow, showing my design in solid lines.

The broken line showing is included for the purpose of illustrating and forms no part of the claimed design.
